UNITED STATES PATENT OFFICE.

ENGLAND J. BARKER, OF MORGAN PARK, ILLINOIS.

AUTOGRAPHIC REGISTER.

SPECIFICATION forming part of Letters Patent No. 793,265, dated June 27, 1905.

Application filed January 8, 1902. Serial No. 88,903.

To all whom it may concern:

Be it known that I, ENGLAND J. BARKER, a citizen of the United States, and a resident of Morgan Park, in the county of Cook and State 5 of Illinois, have invented certain new and useful Improvements in Autographic Registers, of which the following is a full, clear, and exact description.

Heretofore the paper used in autographic registers of the kind to which my invention particularly relates was delivered from several rolls and after being passed around guide-rollers was directed in superimposed layers over a flat bed and carbon-paper or other suitable manifolding material placed between them. The winding of the paper on the roll gives it a set curvature which is difficult to overcome while in the machine, and when the paper is moved to and rests upon the bed in 10 position to be written upon it buckles and is wavy and will not lie flat. In this condition the paper yields under the pressure of the pencil when written upon, and owing to the extra pressure it is necessary to exert on the 15 latter the paper is liable to tear. In addition to this objection the paper when withdrawn from the machine has a tendency to resume its original curvature and refuses to lie flat of its own accord when filed away.

20 The object of my invention is to overcome these difficulties and other inconveniences arising out of the tendency of the paper to curl. This I accomplish by the means hereinafter fully described, and as particularly 25 pointed out in the claims.

In the drawings, Figure 1 is a longitudinal section of an autographic register embodying my improvements. Fig. 2 is an end view of the same. Fig. 3 is a transverse section of 30 the same, taken on dotted line 3 3, Fig. 1. Figs. 4 and 5 are detail views of the clamp for holding the free ends of the paper in alignment with the bed, and Fig. 6 is a perspective view of a package of paper (of exaggerated 35 thickness) used in my invention.

In Fig. 6 of the drawings a package of paper A is shown, which comprises a continuous strip of suitable width folded back and forth, with the layers between each bend laid flat 40 upon each other from top to bottom of the

package. The layers of this package of paper are all of corresponding dimensions and are folded so that their edges are bounded by the same vertical planes, and, if desired, they may be perforated at the bends or folds to facilitate their being torn off after being used. Paper thus folded and made into packages will when drawn over the bed of the register lie very flat and particularly when the proper resistance to their unfolding from the package 55 is provided and their advanced ends are suitably clamped. My invention is especially adapted to utilize in an autographic registering-machine packages of folded paper similar to that just described. 60

The register illustrated in the first five figures of the drawings comprises a stationary section B and a section C, hinged thereto at one end. The stationary section has a suitable rectangular-shaped base *a* of proper dimensions and side walls arising therefrom, the upper edges of the forward portions of which are reduced in height until near the front of the machine they are merely what might be called "continuations" or "extensions" *b* of the lower rail of said side frames. These extensions *b* terminate in lugs, to which the knuckles *c* of the hinged section C are connected by the pintles *b'*. The side frames of the hinged section are connected at the top 70 by the bed D and by suitable cross-bars *d*, and the depth of their under edges is such that when they rest upon the upper edges of the side frames of the section B the height of the machine is the same throughout its length, 75 although this is not essential.

The bed D extends from the front of the machine to a point very near the rear ends of the side frames of the hinged section C, and between its rear edge and the adjacent extremities of the upper rails of said side frames three transverse rollers 2, 3, and 4 are journaled in such a plane that their upper segments are in the same horizontal plane as that of said bed. The paper strips extend from 80 the places where said packages A are located within the confines of the sections B and C to the rollers 2, 3, and 4 and are drawn longitudinally over the bed D to the forward end of the machine, where their advanced edges are 85 90 95 100

suitably clamped within convenient reach of the fingers of the operator.

E represents a case which is arranged longitudinally along one side of the bed of the register and is adapted to contain a roll of one or more sheets of carbon-paper or other suitable manifolding material, which is drawn laterally over the bed, so that a sheet of manifolding fabric will come between each two layers of paper. The case E is normally closed in a suitable manner, and in operation both edges of the paper and the manifolding material are held down upon the bed while the paper is being written upon.

15 In order to hold the strips of paper firmly while being written upon, it is usual to hold the advanced ends of the same, at the end to the bed opposite rollers 2 3 4, by clamping-plates *f* and *g*. The major portions of these 20 plates are adapted to bear flat against each other and are adapted to clamp the paper between them and meet in a plane corresponding to that of the top of the bed, so as to assist in holding the paper flat upon the bed. 25 The rear portions of these plates are suitably bent and formed into sleeves which surround and are secured to transverse rock-shafts G H, journaled in suitable bearings in lugs arising from the upper forward corners of the side 30 frames of the hinged sections of the register. The ends of these shafts project through their bearings at one side of the machine and are provided with segmental gears *m* and *n*, which intermesh. The upper shaft is, as shown in 35 Fig. 5, made spring-returnable, and one of its ends is provided with a horizontally-disposed arm or handle I, by pressing down on which the plates *f* and *g* are separated. When the pressure is relieved from arm I, the torsional 40 action of the spring G' restores it and shafts G and H and plates *f* and *g* to their original positions.

It is desirable in a machine of the kind under consideration to provide some means for 45 holding the ends of the paper adjacent to the clamping-plates *f* and *g* when the latter are opened. I have not shown any devices for this purpose, although I contemplate the use of the same whenever desired.

50 It will be understood that my invention contemplates the use of one or more webs of paper. Where three webs of paper are used, I provide three receptacles, one of which is located in and between the side frames of the 55 hinged section of the machine and the other two of which are located between the side frames of the stationary section. These sections are made by means of transverse partitions 5, 6, and 7 in the stationary section and 60 8 and 9 in the hinged section. The partitions extend from side to side of the machine and rise from the base-plate, to which they are suitably connected, to a suitable point under the bed-plate. At each end of each of 65 these receptacles are spring-depressible guide-

rollers *k* *k'*, which are adapted to bear down upon the folded ends of the package of paper to prevent the same from paying out too rapidly. The roller *k'* of each receptacle, located nearest the left-hand end of each receptacle, 70 as shown in Fig. 1, simply bears down upon the uppermost layer of paper. The roller *k* at the opposite end, however, while bearing down upon the paper is adapted to have the web of paper pass around it and run from 75 thence to rollers 2, 3, and 4. This always offers sufficient resistance to the paying out of the web of paper that it is taut from the moment it leaves the receptacle in which the package it belongs to is placed until it leaves the machine. These resistance-rollers *k* *k'* are journaled either directly in bearing-blocks *k*², having vertical play in the perpendicular slots *k*³, made in the side frames of each section, or in arms extending therefrom, and between said bearing-blocks and the upper ends of said slots coil expansion-springs *k*⁴ are placed, that always keep said blocks and rollers bearing downward. Each of these receptacles in which packages A are placed 80 is provided with false bottoms K, upon which the package of paper is placed, and under these bottoms K are springs M and O and spring-post N, that are supported on the base-plate *a* and push upward against said bottoms K, so as to always keep the folded edges of the packages bearing up against the rollers *k* *k'*. In order to limit the downward movement of bottoms K, I can, if desired, provide the partitions with vertical slots *r*, 85 preferably located about their centers of length, and provide said bottoms with tenons which enter the slots *r* and not only limit the downward movement of said false bottoms, but also serve to guide and steady the movement of the same. 90

As paper is wanted upon the bed the clamping-plates *f* and *g* are opened and the projecting ends of the papers grasped and drawn forward as far as desired. The clamping-plates are then closed, and the paper so withdrawn from the machine is torn off. The paper thus moved over the bed is pulled from the top of the packages A in the receptacles inclosed in the machine below the bed. In so doing sufficient resistance is offered by the engagement of the folded ends of said packages by the rollers *k* *k'* that the paper will not pay out too rapidly and so that when the paper is in proper position on the bed the stretch 100 thereof between the rollers 2, 3, and 4 and the receptacles in which the paper packages are placed will be taut. Thus it will be observed the paper is not only kept in straight layers while in the original package, but the tendency of the paper to curl either when on the bed or when withdrawn from the machine is practically obliterated. From the receptacles to the reversing-rollers 2, 3, and 4 and from the said rollers to the clamping-plates the pa- 105 110 115 120 125 130

per is held tight and when written upon does not yield under pressure and buckle, crease, or tear.

The placing of the packages of paper in the receptacles of the stationary section is a very easy matter. All that has to be done is to lift the swinging section and the packages can be deposited in place without difficulty. The package can be placed in the receptacle 10 in the hinged section by shoving it in endwise between the side frames thereof, over the partition 9, and then letting it drop into place. I prefer, however, to hinge the lower edge of said partition by a returnable spring-hinge 10 and simply swing said partition down while the package is being deposited on platform K. When the package is once in place, the partition is permitted to swing back to the normal vertical position shown in Fig. 1.

20 What I claim as new is—

1. In an autographic register the combination with a flat bed of several receptacles located below said bed and each containing a package of paper, means for directing the 25 course of the paper unfolded from said package in each of said receptacles to one end of said bed and devices for temporarily confining said strips in superimposed layers upon said bed comprising spring-controlled clamping-plates operatively connected with each 30 other by means of corresponding gears.

2. In an autographic register the combination with a flat bed of several receptacles located below the same and each containing a 35 package of paper, a series of rollers located at one end of said bed to and around which the paper paid out from said receptacles passes, and is directed in superimposed layers over said bed, and devices for temporarily confining 40 said superimposed layers of paper upon said bed comprising spring-controlled clamping-plates operatively connected with each other by means of corresponding gears.

3. In an autographic register the combination 45 with a flat bed of several receptacles located below the same and each containing a package of paper, a series of rollers located at one end of said bed to and around which the paper paid out from said receptacles passes 50 and is directed in superimposed layers over said bed, devices for temporarily confining said superimposed layers of paper upon said bed, and means for clamping the ends of said paper at the end of the bed opposite said rollers within convenient reach of the operator 55 comprising spring-controlled clamping-plates operatively connected with each other by means of corresponding gears.

4. In an autographic register the combination 60 with a flat bed of several receptacles located below the same and each containing a package of paper, a series of rollers located at one end of said bed to and around which the paper paid out from said receptacles passes 65 and is directed in superimposed layers over

70 said bed, devices for temporarily confining said superimposed layers of paper upon said bed, two clamping-plates, shafts from which the same project one of which is located above the other and the other of which is automatically returnable, intermeshing gears on the ends of said shafts, and a depressible arm projecting from the upper of said shafts, said clamping-plates being adapted to clamp the ends of the papers extending over said bed at the end 75 thereof opposite said rollers.

5. In an autographic register the combination 80 with a stationary section and a hinged section the top of which forms the bed of the register and is adapted to cover said stationary section, receptacles below said bed and each adapted to contain a package of paper, resistance-rollers bearing down upon the ends of said packages, and devices for guiding the webs of paper therefrom to and holding them 85 upon said bed while said sections are closed together.

6. In an autographic register the combination 90 with a stationary section, and a hinged section the top of which forms the bed of the register and is adapted to cover said stationary section, receptacles below said bed adapted to contain a package of paper, rollers adapted to yieldingly resist the paying out of the web of paper therefrom, upwardly-pressing 95 false bottoms for the same, and devices for guiding said paper to and holding the same upon said bed while said sections are closed together.

7. In an autographic register the combination 100 with a stationary section and a hinged section the top of which forms the bed of the register and is adapted to cover said stationary section, receptacles below said bed adapted to contain a package of paper, rollers adapted to yieldingly resist the paying out of the web of paper therefrom, a movable false bottom in each of said receptacles, springs normally pressing upward against the same, and devices for guiding said paper from said receptacles and holding the same upon said bed while said sections are closed together.

8. In an autographic register the combination 105 with a stationary section and a hinged section the top of which forms the bed of the register and is adapted to cover said stationary section, receptacles below said bed adapted to contain packages of paper, rollers adapted to yieldingly resist the paying out of the webs of paper therefrom, means for imparting an 110 upward pressure to the packages of paper contained therein against said rollers, and devices for guiding said webs to and holding them upon said bed while said sections are closed together.

9. In an autographic register the combination 115 with a stationary section and a hinged section the top of which forms the bed of the register and is adapted to cover said stationary section, receptacles below said bed adapted to 120

125

130

contain a package of paper, normally depressed rollers adapted to yieldingly resist the paying out of the web of paper therefrom, means for imparting an upward pressure to the package of paper contained therein against said rollers devices for guiding said paper to and holding it upon said bed while said sections are closed together, operatively-connected clamping-plates at the end of the bed for holding the ends of said paper.

10. In an autographic register the combination with a stationary section and a hinged section the top of which forms the bed of the register and covers said stationary section, means for supplying strips of paper inclosed in said sections below said bed, over which bed said strips are extended longitudinally from one end of the same to the opposite end thereof, and upper and lower normally engaging 20 hinged clamping-plates that are journaled at said other end of the bed and meet in a horizontal plane corresponding to that of said bed.

11. In an autographic register the combination with a stationary section and a hinged section the top of which forms the bed of the register and covers said stationary section, means for supplying strips of paper inclosed in said sections below said bed, over which bed said

strips are extended longitudinally from one end of the same to the opposite end thereof, 30 and upper and lower normally engaging automatically-returnable and operatively-connected hinged clamping-plates that are journaled at said other end of the bed and meet in a horizontal plane corresponding to that of said bed. 35

12. In an autographic register the combination with a stationary section and a hinged section the top of which forms the bed of the register and covers said stationary section, means for supplying strips of paper inclosed in said sections below said bed, over which bed said strips are extended longitudinally from one end of the same to the opposite end thereof, 40 upper and lower normally engaging hinged clamping-plates that are journaled at said other end of the bed, and meet in a horizontal plane corresponding to that of said bed and the journals of which extend through their 45 bearings, gears that engage each other secured to said extensions and means for automatically returning said plates into engagement. 50
